VENETIAN BLIND COVER

Marion E. Skwark, Binghamton, N. Y.

Application October 3, 1951, Serial No. 249,480

6 Claims. (Cl. 160—34)

1

This invention relates to covers for Venetian blinds and more particularly to transparent covers to enclose the blinds in order to protect them against the gathering of dust and the like.

In recent years the modes of fashion have laid particular emphasis on the appearance of windows in houses, and pursuant to this the Venetian blind had progressed in popularity. It has become more popular because in addition to its esthetic appeal it has the unique ability of regulating the amount of light which passes therethrough while to some extent permitting one to look through the entire area of the window before which the blind is arranged. One disadvantage, however, characteristic of such blinds, is their tendency to gather dust and the consequent extreme difficulty in keeping them clean.

It is therefore an object of this invention to provide a means of eliminating this previously mentioned difficulty while still permitting efficient operation of the blind to control the amount of light passing therethrough and while still permitting one to obtain a view through the window inhibited only by the elements of the Venetian blind.

More particularly, it is an object of this invention to provide a cover for Venetian blinds while still allowing the blinds to operate in the same efficient manner as before and to perform their same function.

In addition to the above and foregoing, it is a further object of this invention to provide a single cover for use with Venetian blinds of varying dimensions. This is accomplished generally by arranging the cover with means to permit suitable adjustments both widthwise or lengthwise. The means to permit adjustments is fashioned to produce a curtain or drapery effect so that the resulting article is a combination Venetian blind cover and curtain or drape, and thereby serves the added function of acting to beautify the appearance of the article as well as that of the blind which it encases.

Broadly this invention relates to a transparent cover for a Venetian blind which will cooperate with the blind to protect it from gathering dust. The cover is mounted to a casing surrounding the Venetian blind head and encloses the slats thereof. The cover is arranged to permit outside control of the blind and has means to prevent the interference of the cover with the free operation of the blind.

Other and further objects of the invention will become apparent from the following detailed description of the drawings.

2

Figure 1 is a view in perspective of the Venetian blind cover of the present invention;

Figure 2 is a view in top plan of the cover of Figure 1;

Figure 3 is a view in rear elevation of the cover of Figure 1;

Figure 4 is a view in vertical section of Figure 1 taken along the line 4—4;

Figure 5 is a view in vertical section of Figure 1 taken along the line 5—5;

Figure 6 is a view in perspective of the cover of Figure 1 showing the manner in which it is opened;

Figure 7 is a view in horizontal section of Figure 1 taken along the line 7—7;

Figure 8 is a view in horizontal section of Figure 1 taken along the line 8—8;

Figure 9 is a view in perspective showing a modified cover;

Figure 10 is a view in perspective similar to Figure 9 showing in greater detail the top construction of the cover;

Figure 11 is a view in vertical section of Figure 9 taken along the line 11—11;

Figure 12 is a view in vertical section of Figure 9 taken along the line 12—12;

Figure 13 is a view in horizontal section of Figure 9 taken along the line 13—13;

Figure 14 is a view in horizontal section of Figure 9 taken along the line 14—14;

Figure 15 is a view in elevation showing a modified means for permitting adjustment of the cover; and

Figure 16 is a view in elevation similar to Figure 15 showing the modified means in greater detail.

Referring now to the drawings, Figures 1 to 8, inclusive, show the Venetian blind cover of the present invention. The front of the cover consists of a central panel 20 preferably made of a transparent clear stiff plastic and two side panels 22 preferably made of a softer more flexible plastic material.

The central panel 20 is joined to the side panels 22 by any suitable means; however, for purposes of illustration this can be accomplished by sewing the panels together with a thread 24 as shown in Figure 8. The back of the cover is constructed similarly to the front and consists of a central panel 26 having sewn there-

to by suitable means such as thread 28 side panels 30. A binding strip 31 is sewn to the top and bottom of each of the central panels 20 and 26.

The front and back of the cover are joined by means of end panels 32 made of the same mate-

rial as the central panels 20 and 26.

3

rial as panels 22 and 30. This connection can be made by any suitable means, but for purposes of illustration, it is shown as being effected by appropriately sewing the panels together by thread 34 (see Figure 7).

The side panels 22 and 30 of the front and back, respectively, of the cover are arranged at their top and bottom with elastic bands 36 which have been sewn into pockets 38 formed in the side panels by folding the material of the side panels back on itself and stitching with a double row of thread 40. The elastic bands 36 are sewn into pockets 38 under tension so that they will produce a shirred effect as indicated at 42 (see Figure 1).

The bottom 44 of the cover is sewn to the central, side, and end panels previously described to close off the cover. The bottom 44 is of the same material as the side panels 22 and 30. The bottom 44 is arranged at either end with a pair of elastic bands 46 coextensive with bands 36 which have been sewn into pockets 48 formed by folding the material of the bottom at either end back over itself as shown in Figure 4 and stitching with a double row of thread 50. The elastic bands 46 are sewn into pockets 48 under tension so that a shirred effect will be produced.

The top of the cover consists of a rear panel 52 which has one edge 54 sewn to the back of the cover. To the other edge 56 of the rear panel 52 is sewn one edge 58 of an upper panel 60. To the other edge 62 of the upper panel 60 is sewn the other edge 64 of a forward panel 66. The other edge 68 of forward panel 66 is provided with a series of spaced interlocking fastener elements 70. The top edge of the front of the cover is provided with a series of spaced interlocking fastener elements 72 in complementary relation for cooperation with the elements 70. When the fastener elements 70 and 72 are interlocked, the cover assumes a box-like shape.

The upper panel 60 projects beyond the rear panel 52 and forward panel 66 at either end. These projecting portions 74 of panel 60 are provided on their under surface with a pair of interlocking fastener elements 76. Each of the panels 52 and 66, has sewn thereon at either end a triangular piece 78, each of which is arranged with an interlocking fastener element 80 for cooperation with one of the elements 76. When the top of the cover is in the closed position as shown in Figures 1, 4 and 5, the elements 76 and 80 are interlocked. Defined between the portion 74, pieces 78 and the top edge 82 of the end panel 32 is an opening 84, the function of which will be fully explained hereinafter.

Each of the panels 52, 60 and 66 is arranged at its ends with a pair of elastic bands 86 coextensive with bands 36 and 46 which have been sewn into pockets 88 formed by folding the material of the panel back over itself as shown in Figure 4 and stitching with a double row of thread 90. The bands 86 are sewn into pockets 88 under tension so that a shirred effect will be produced.

Attached to edge 64 of panel 66 at either end coextensive with side panels 22 is one edge 92 of a flap-like member 94. This attachment can be made by any suitable means. However, for purposes of illustration the panel 66 and member 94 are shown sewn together. The members 94 are each arranged with an elastic band 96 which is sewn into a pocket 98 formed by folding the material of member 94 back over itself as shown in Figure 4.

and stitching with a double row of thread 100. The band 96 is sewn into pocket 98 under tension so that a shirred effect is produced as indicated at 102.

The bottom edge of the side panels 22 of the front of the cover are each provided with a pair of interlocking fastener elements 104 which cooperate with a complementary pair of interlocking fastener elements 106 mounted on a flap-like member 107, substantially similar in construction to flap-like members 94. By this arrangement the members 107 are detachable and hence can be readily removed when desired. Each of the side panels 22 is also provided with an interlocking fastener element 108 at its outside edge approximately midway between its ends which cooperates with a complementary interlocking fastener element 110 mounted on the end of a tab 112 sewn to the bottom outside corner of each of the side panels 30 of the back of the cover.

In use the cover of the present invention is placed about a Venetian blind as follows. The top of the cover is opened as shown in Figure 6, thereby presenting the cover as an open-ended box-like structure. In this condition the blind is placed inside the cover. The top of the cover is thereafter fitted over the top of the blind and the fastener elements 70 and 72 are mated, thereby closing the cover. The elements 76 and 80 are then mated, resulting in opening 84 to permit the necessary parts of the blind to protrude therethrough for the purpose of permitting attachment of the blind to a window pane structure or the like. In order to operate the blind without the necessity for removing the cover, reinforced slits 114 are provided in side panels 22 of the front of the cover whereby the cords of the blind can pass outside of the cover to permit their manipulation.

The various elastic bands of the cover serve to make it adjustable for Venetian blinds of different widths while at the same time insuring a tight fit between the blind and the cover for any given width. Also, the bands produce a shirred effect, as previously described, and in this manner the portions of the blind so affected simulate curtains and drapes, thereby greatly enhancing the appearance of a blind so enclosed. To this end the central panels 20 and 26 of the front and back of the cover can be made of a stiff transparent material and the remainder of the cover can be made of a softer plastic material which is either transparent, translucent or opaque. It is preferred, however, that the remainder of the cover be made of a translucent material which has thereon a surface ornamentation.

A modified form of this invention is shown in Figures 9 to 14, inclusive. The cover shown here consists of a front, back and bottom substantially similar to the corresponding parts of the cover of Figure 1 with the exception that the flap-like members 120 corresponding to flap-like members 107 are permanently attached to the bottom edge of the front of the cover instead of removably attached. The end panels 122 of the cover join with the front, back and bottom of the cover as previously described and are provided at their tops with slide fasteners 124. The top of the cover is permanently attached to the back and front of the cover and includes a forward panel 126, a rear panel 128 and an upper panel 130, which has projecting pieces 131 sewn to the other panels. Each of these panels is ar-

ranged with a pair of elastic bands 132 which run coextensive with the elastic bands 134 located at the top of the front of the cover. The bands 132 are sewn into pockets 136 formed in the panels by folding the material of the panels back over itself and stitching with a double row of thread 138. The bands 132 are sewn into pockets 136 under tension to produce a shirred effect.

Another series of elastic bands 140 are similarly sewn into the panels 126, 128 and 130 transversely of the bands 132. Also flap-like member 142 is attached to the top of the cover as shown. This member 142 extends for the length of the top of the cover.

The function of bands 132 was described in conjunction with Figures 1 to 8, inclusive. The bands 140 in addition to insuring a tight fit between the cover and blind and producing a desired effect also result in making the cover adjustable to blinds of various lengths. Hence, the cover of Figures 9 to 14, inclusive, presents a cover which is adjustable to blinds of varying widths and lengths. It is important to note in this regard that the construction of the cover is such that whatever adjustments that must be made between the cover and the blind are accomplished by the cover automatically and without the necessity for manual operation upon any part of the cover.

In order to encase a Venetian blind with the cover of Figures 9 to 14, inclusive, the blind is conditioned so that it is in its retracted position. Thereafter, the slide fasteners 124 are opened and the blind is put into the cover. The fasteners are then closed.

A modified arrangement to be utilized in lieu of the elastic bands is shown in Figures 15 and 16. The material of the cover is represented by numeral 150. In place of an elastic band, a resilient thread 152 is employed. In affixing the thread 152 to the material 150, a second thread 154 is employed in the form of a cross stitch. As shown in detail in Figure 16, the thread 152 lies directly beneath the material 150. The thread 154 is passed through material 150 from above, wound around thread 152, and thereafter passed through material 150 to above. This operation is successively repeated. During the above, thread 152 is under tension so that it will produce a shirred effect after it has been affixed to the material 150.

As can be seen, the flexible thread 152 can be used in place of the elastic bands or in combination therewith.

While the above and foregoing invention has been described in conjunction with specific embodiments, nevertheless various changes and modifications obvious to one skilled in the art are within the spirit, scope, and contemplation of the preferred invention.

What is claimed is:

1. A cover for a Venetian blind of the type consisting of a blind head operatively connecting a plurality of slats through the agency of a bottom bar that comprises a series of horizontal and vertical panels arranged in a box-like structure adapted to receive a Venetian blind and completely enclose same and elastic means adapted to cooperate with the top portions of the cover, which enclose the blind head of an enclosed Venetian blind, to allow the cover to change its dimensions in a direction longitudinally of the head.
2. A cover as defined in claim 1 wherein further elastic means are provided adapted to cooperate with the bottom portions of the cover, which enclose the bottom bar, to allow the cover to change its dimensions in a direction longitudinally of the bottom bar.
3. A cover as defined in claim 1 wherein further elastic means are provided adapted to cooperate with the portions of the cover surrounding the head to allow the cover to change its dimensions in a direction transversely of the head.
4. A cover as defined in claim 1 wherein said elastic means is constituted by an elastic strap sewn into the cover in a tensioned condition.
5. A cover as defined in claim 2 wherein said elastic means at the top and bottom of the cover are constituted by a plurality of elastic straps sewn into the cover while in a tensioned condition thereby to produce a shirred effect.
6. A cover as defined in claim 1 wherein said elastic means is constituted by an elastic thread affixed to the cover in a tensioned condition.

MARION E. SKWARK.
